[57] **CLAIM**

The ornamental design for a combination pull tab can and bottle opener, as shown and described.

DESCRIPTION

FIG. 1 is a front elevation of a combination pull tab can and bottle opener showing my new design;

FIG. 2 is a right side elevation thereof;

FIG. 3 is a rear elevation thereof;

FIG. 4 is a top plan view thereof;

FIG. 5 is a bottom plan view thereof;

FIG. 6 is a left side elevation thereof;

FIG. 7 is a front elevation of a second embodiment of that shown in FIG. 1;

FIG. 8 is a right side elevation of that shown in FIG. 7; and

FIG. 9 is a rear elevation of that shown in FIG. 7.

FIG.1FIG. 2FIG. 3FIG. 4FIG. 5FIG. 6FIG. 7FIG. 8FIG. 9
